UNITED STATES PATENT OFFICE

DAVID ISHbia, OF NEW YORK, N. Y.

TAXIMETER AND SIGNAL OPERATING MECHANISM THEREFOR

Application filed August 20, 1931. Serial No. 558,212.

This invention relates to signs adapted to be used on taxicabs and the like taximetered devices so as to indicate whether the same are occupied or vacant. This invention is an improvement in the invention disclosed and claimed in copending application Serial No. 466,482 filed July 8, 1930, entitled "Variable illuminated sign".

The particular type of illuminated sign disclosed and claimed in my co-pending application comprises an illuminated panel mounted upon the taxicab, in front of which is positioned a slideable shutter arranged and adapted to uncover in one position the word "Vacant" and in a second position the word "Occupied". Means are provided to shift the shutter to either position to correspond with the position of the taximeter flag which is located within the body of the cab.

Ordinarily the taximeter includes a lever arm to which is attached a taxi flag or sign, which lever arm is adapted to render the meter device operative and inoperative. Usually when the lever arm is in an upright position the meter is inoperative; when in a downward position the meter is operative. The taxi flag, therefore, usually carries the word "Vacant" which is displayed when the lever arm is extending upward.

In my prior application it was one of the objects to provide means to automatically operate the shutter of the luminous sign when the lever arm of the taximeter is moved from the inoperative to the operative position and vice versa.

One of the objects of the present invention is to provide an improved automatic means to operate the illuminated sign shutter.

Another object of this invention is to provide a unit shutter operating device adapted to be attached to a standard taximeter without altering the same.

Another object of the present invention is to improve the automatic operation of the illuminated sign of my prior invention.

Other objects and advantages will be apparent as the invention is more fully disclosed.

In accordance with the objects of my invention I have devised an improved auto-

matic shutter operating means which comprises a compact unit mechanism adapted to be attached directly to the taximeter lever shaft and thence through an extensible member to the movable shutter of the luminous sign, and adapted to displace the shutter from one to another position and return upon movement of the taximeter lever arm from the inoperative to operative position and return.

Before further disclosing the nature and scope of the present invention reference should be made to the accompanying drawings wherein—

Fig. 1 is a front elevation of a portion of a taxicab showing the illuminated sign positioned therein;

Fig. 2 is a side elevation of the same;

Fig. 3 is an enlarged plan view partly in section showing the elements of the present invention;

Fig. 4 is a view taken along plane 4—4, Fig. 1;

Fig. 5 is an enlarged sectional view of the unit shutter operating means of the present invention;

Fig. 6 is a second view of the same showing the elements in operating engagement;

Fig. 7 is a third view of the same;

Fig. 8 is a fourth view of the same;

Fig. 9 is a perspective view of the casing enclosing the operating elements;

Fig. 10 is a perspective view of the remaining elements comprising the unit shutter operating means; and

Fig. 11 is a perspective view of the shaft adapter of the unit shutter operating means.

Referring to the drawings Figs. 1, 2 and 3, an illuminated sign 1 is mounted upon the body of a taxicab 2 preferably in the position shown, and connected by suitable means 3 to a taximeter 4 in such manner that when the taximeter lever arm supporting flag 5 is in the upright or "Vacant" position indicated in Fig. 1 the letters in the illuminated sign 1 shall spell the word "Vacant", and when the flag 5 is in the depressed or "Occupied" position indicated in Fig. 2 the letters in the illuminated sign 1 shall spell the word "Occupied".

The particular manner in which the taximeter flag 5 and illuminated sign 1 are coordinated is shown in greater detail in Fig. 3. The illuminated sign is comprised of an illuminated panel 10 and a shutter 11, comprised of a plurality of slidably connecting metal sheets each having a plurality of openings therein, the openings coinciding in one position to spell out the word "Vacant" in illuminated letters, and in a second position to spell out the word "Occupied" in similar illuminated letters.

Means 3 are provided to shift the shutter from one position to the other, comprising spring tension members 12 and 13, flexible cable 14 and wire 15 interiorly positioned in cable 14. Wire 15 is attached at one end to one end of spring tension member 13. The other end of spring 13 is attached to one of the slidable shutters 11. One end of spring member 12 is attached to the other end of the slidable shutter 11 and the other end of spring 12 is fastened securely to the frame of the sign 1.

23 In this arrangement of elements a pull exerted upon the free end of wire 15 in cable 14 will act through spring 13 to displace the shutter 11 against the tension in spring 12. When the force exerted to displace the shutter is released the tension in spring 12 will return the shutter to its first position.

I apply the necessary force or pull upon wire 15 by the device and mechanism illustrated with particularity in Figs. 4 to 11 inclusive. 25 The end of wire 15 is attached to a toothed member 16 which is adapted to be meshed with a gear 17. Gear 17 is keyed to shaft 19 which is adapted to be secured upon shaft 19 (Fig. 4) of the taximeter so as to be rotatable therewith. Tooth member 16 and gear 17 are enclosed within a housing 20 comprised of sheet metal and preferably shaped and formed in two sections 20 and 21 as illustrated in Fig. 9.

30 In the usual taximeter device when the flag 5 is in the upright or vacant position the taximeter is in an inoperative position. When the flag 5 is depressed to the position indicated in Fig. 2 the taximeter is in an operative position. The taximeter is fixed so that the meter flag and shaft 19 may be rotated only in one direction, so that the flag must be returned to the upright or vacant position by a completion of the 360° rotation of the flag 5. This is indicated by arrows upon the flag 5 in Figs. 5 to 8 inclusive.

35 Therefore when the shutter 11 is in position to form the word "Vacant" to correspond with the flag 5 the toothed member 16 must be in a position to the left of the gear 17 as indicated in Fig. 5 and the cut away portion of the gear 17 must be positioned as indicated. As the flag 5 is depressed to a downward position the meshing of the teeth of gear 17

with the teeth of member 16 is adapted to move the member 16 preferably from left to right so as to exert a pull upon wire 15 thus moving shutter 11 from its fixed position against the tension of spring 12. A reverse 70 rotation of shaft 19 is impossible so the tension of spring 12 does not tend to disturb the fixed position of the elements until a complete rotation of the shaft is obtained and the cut away portion of the gear 17 appears. The 75 spring tension means 12 is then used as a means of returning the member 16 and shutter 11 to the desired initial position when the gear 17 has completed its rotation and flag 5 is again in an upright or vacant position. 80

Many modifications and adaptations of the shutter operating means of the present invention may be devised but that illustrated in Figs. 4 to 11 inclusive appears to be the most practical under present conditions. 85 The parts illustrated may be assembled into a compact unit within the housing 20 and shaft 18 may be provided with an extension 22 on one end that is adapted to be positioned on the end of shaft 19 in place of flag 5 90 and to be pinned or keyed thereto in any convenient manner. For illustration purposes pins 23 are shown in Fig. 10. The other end of the shaft 18 may be provided with an extension that is adapted to serve to position 95 flag 5 thereon. Gear 16 may be pinned or keyed to shaft 18 or the shaft may be squared or shaped in any convenient manner to receive the gear. Means are provided at one end to attach wire 15 to member 16. 100

The assembled shutter operating means merely needs to be mounted upon the taximeter shaft 19 as illustrated in Fig. 4 and wire 15 attached to member 16 as indicated in the drawings. 105

Having broadly and specifically described the present invention, such modifications and departures from the specific embodiment disclosed herein are contemplated as may fall within the scope of the following claims. 110

What I claim is:

1. An illuminated sign for taxicabs and the like devices, utilizing a taximeter including a lever for rendering the meter operative and inoperative, comprising a sign housing adapted to be supported upon a cab, an illuminated panel therein, and a movable shutter therefor adapted to be displaced into a plurality of positions and to uncover in one position one set of illuminated letters, and in a second position another set of illuminated letters, spring tension means to retain the shutter in a predetermined fixed position, means operatively connected to the lever arm of said meter device to displace the shutter from its fixed position when the lever is thrown from the inoperative to the operative position, said means comprising an extensible wire member adapted at one end to engage the shutter at a side opposite to the side 120

thereof engaged by the spring tension means and adapted at the other end to be connected to the lever arm through means comprising a movable member adapted to be meshed with a rotatable gear keyed upon the lever arm shaft, the degree of movement imparted to the movable member by a rotating of the gear being sufficient in amount to effect the desired tensional displacement of said shutter and means to release the displacing means upon a return of the lever to its first position.

2. An illuminated sign for taxicabs and the like devices, utilizing a taximeter including a lever for rendering the meter operative and inoperative, comprising a sign housing adapted to be supported upon a cab, an illuminated panel therein, and a movable shutter therefor adapted to be displaced into a plurality of positions and to uncover in one position one set of illuminated letters, and in a second position another set of illuminated letters, spring tension means to retain the shutter in a predetermined fixed position, means operatively connected to the lever arm of said meter device to displace the shutter from its fixed position when the lever is thrown from the inoperative to the operative position, said means comprising an extensible wire member adapted at one end to engage the shutter at a side opposite to the side thereof engaged by the spring tension means and adapted at the other end to be connected to the lever arm through means comprising a movable member adapted to be meshed with a rotatable gear keyed upon the lever arm shaft, the degree of movement imparted to the movable member by a rotating of the gear being sufficient in amount to effect the desired tensional displacement of said shutter and means to release the displacing means upon a return of the lever to its first position comprising adapting the gear through the provision of a cut away periphery section to release the movable member, the spring tension means thereby functioning to return the shutter and movable toothed member to their preferred and fixed position.

3. In combination a taximeter including a lever arm for rendering the meter operative and inoperative, an illuminated sign including an illuminated panel, and a movable shutter adapted to uncover in one position one set of illuminated letters on said panel and in a second position a second set of letters, and means to move said shutter, said means comprising a cut gear keyed to a shaft adapted to be attached to the lever arm shaft of said meter, a movable member adapted to mesh through a prescribed orientation with said cut gear, an extensible member connected at one end with said movable member and at the other end with the movable shutter, and spring tension means adapted to return the shutter and movable member to their first

positions upon a termination of the preferred orientation of said gear.

4. A device adapted to be mounted upon a taximeter lever shaft comprising a housing, a movable toothed member contained therein, a cut gear adapted to intermesh with said toothed member through a prescribed orientation about its axis, a shaft extending through the housing and carrying said gear keyed thereto, adapter means to attach one end of the shaft to the taximeter lever shaft so as to rotate therewith, and means to attach the movable toothed member to an extensible wire member.

5. In an illuminated sign adapted for use on a taxicab and the like devices utilizing a meter device including a lever adapted to render the meter operative and inoperative, means coordinating the legend of said sign with the operative and inoperative position of said lever, comprising a housing, a toothed movable member and a cut gear member adapted to intermesh therewith contained in said housing, a shaft extending therethrough upon which the cut gear is keyed, means to attach one end of said shaft to the lever shaft, means to attach the lever arm to the other end of said shaft, and means to connect the toothed movable member to the sign legend operating means.

In witness whereof, I have hereunto signed my name.

DAVID ISHBIA.
